HAND MIRROR AND THE LIKE

Alfred F. Reilly, North Attleboro, Mass.

Application October 8, 1941, Serial No. 414,211

5 Claims. (Cl. 88—102)

The invention relates to hand mirrors and particularly to the production and employment and mounting of a hand mirror frame made of a more or less valuable metal, especially such as silver or the like. Fine or sterling silver is a soft metal and in order to produce a frame all of silver having a sufficient rigidity a considerable quantity of silver must be employed and the frame or casing must be either solid or made of a thick shell of silver. Such an arrangement, however, is expensive. It is a purpose of the present invention to provide an arrangement by which a sufficiently strong, sturdy and useful frame may be made with a very thin sheet of silver. To this end sufficient reinforcement at proper points is employed to hold the frame in proper form to keep it from deforming and to reinforce the metal so that the surface is not readily deformed by casual blows or contact with rough or heavy articles. In such devices it is not unusual to make a number of different patterns having different surface chasing or different colors or ornamentations of enamel or the like applied to at least a portion of the back so as to satisfy the various tastes of individuals who are to purchase or use the article. Since it cannot be known in advance how many of each pattern may be demanded a simplified method of providing an indefinite number of devices of each pattern in an economical manner may be desirable. The present invention contemplates, therefore, providing a more or less standard frame, or a plurality thereof, so constructed that the mirror may be inserted and exposed to view from one side while on the back or other side there may be inserted a separate ornamental back member. The frame itself may be made in considerable quantity and the separable back members may be made in a number of different patterns so that when orders are received the desired back may be assembled with the frame and the demanded article may be promptly and economically furnished. By making the back insert and the frame separate there is, of course, a considerable economy in both manufacture and overhead involved in the expense necessary to keep a considerable number on hand. Since the back is a separate piece from the frame it may be worked or ornamented as a separate unit. Errors, mistakes and defects in the back will not necessitate discarding the frame member and likewise mistakes in manufacture, etc., of the frame may not require the necessity of discarding the back which would be necessary if the back were integral with the frame.

A frame member more or less U-shaped at its edge may be formed with inwardly turned flanges at both front and back. The frame member in general outline may be oval or circular or any shape desired for the exposure of the mirror. The frame may be provided with a hollow handle. This entire unit may be made of thin sheet silver. Engaging the inturned flange at the back may be inserted a back plate member which may be of thin sheet silver and may at its periphery be provided with a flange to engage the flange in the back of the frame. When this has been put in place there may be cemented to it a reinforcing member of cardboard or the like. Preferably the reinforcing member will be substantially the same size as the back member and may thus reinforce its entire surface. The edges of the reinforcing member may be in direct contact with the inturned flanges of the back insert and so tend to hold them in position to surely engage the flanges at the back of the frame. In order to keep the entire structure rigid a small stick, preferably of wood, may be inserted all or part way into the hollow stem and the hollow stem may then have put into it a suitable cement which when set may form a reinforcement for the hollow handle strengthening it and tending to hold it in shape. The cement at the same time may hold in place the stick which will be partly embedded in the cement. From the handle the stick may extend across the frame and its end may engage the frame opposite the handle thus tending to aid in holding the frame in extended position and also reinforce it against bending. On each side of the stick may be placed a reinforcing member of thin plywood or the like, and each reinforcing member may extend from the stick outward toward the side and into the frame member itself. Each reinforcing member thus may overlie and be in contact with about half of the flange on the back insert plate. The reinforcing strips on each side of the stick may tend to press against the flange and hold it in contact with the flange on the back of the frame and thus hold the insert plate in proper position. Within the front of the frame overlying the stick and the two side reinforcing members may be placed a reinforcing member of cardboard or stiff corrugated cardboard or the like. This may be of the same shape and about as large as the opening in the frame. The mirror then, when put in place and held in place by a bezel, will in effect press upon the last mentioned insert member and tend to press the various parts more or less tightly together and so hold the back insert

firmly and neatly in place so as to keep its flange in close supporting contact with the flange on the back of the frame.

The arrangement lends itself to the production of an economical, sturdy device which may supply the long existing want for a satisfactory hand mirror made of silver but at the same time cheap enough to sell for a moderate retail price and simple and variable enough to make its manufacture to meet various demands economical.

In the accompanying drawing Figure 1 is a front plan view of a hand mirror, portions being broken away to show the construction and reinforcement. Fig. 2 is a fragmentary transverse vertical section on an enlarged scale on the line 2—2 of Fig. 1.

There may be provided a frame 10 which as shown in Fig. 2 has an inwardly turned flange 11 about the opening in its face in which a mirror 12 may be held in any suitable way as by means of a bezel 13. At its opposite or back side the frame has a similar opening surrounded by an inwardly turned flange 14. In the back opening is a plate 15 which is structurally separate from the frame 10 and which may be ornamented in any suitable manner. The plate 15 is provided with a more or less U-shaped flange 16 throughout its periphery which is adapted to hook over and engage the flange 14. In this manner the plate 15 is held in place closing the rear opening in the frame 10. The frame 10 and the plate 15 may both be made of fine silver of the grade necessary to carry the mark "sterling." Since this metal is expensive it is desirable that the parts be made as thin as possible to answer their purpose. In order to hold the thin plate 15 in shape there may be inserted in it a sheet 17 of cardboard or the like. This sheet 17 will preferably be cut just small enough to stay inside the flange 16. It may be cemented to the plate 15 and when the cement hardens it will form a more or less sturdy, rigid back for the plate 15 and not only hold it in proper form but tend to prevent it from being deformed or dented by casual or accidental contact with hard articles. It will be noted that the edge of the reinforcing member 17 engages the upwardly extending rim of the U-shaped flange 16 and so tends to press it outward and into contact with the flange 14 in the frame member 10. Thus the joint on the back of the mirror may be strong and neat and there may thus be prevented any tendency to gap. The frame 10 may be reinforced and strengthened by a stick or rod 18 which preferably may be made of wood. The stick 18 may be inserted a suitable or short distance into the handle 19 of the frame and will be long enough to extend between the flanges of the frame 10 opposite the handle. The hollow handle 19 may be more or less filled with a cement or the like 20 which will hold the stick 18 in proper reinforcing position and also when solidified may act as an internal reinforcement for the handle 19 which itself, like the rest of the frame, will preferably be made of very thin, soft silver.

To reinforce and hold in place the parts of the device there may then be provided at each side of the stick 18 an insert plate 21, made of thin plywood or especially stiff cardboard or the like. Each insert plate 21 may be in area nearly half the opening in the frame 10 so that when placed at the side of the stick 18 it will extend part way into the sides of the frame 10 and at its edge overlie and rest upon the flange 16, thus

tending to hold it securely in contact with the flange 14 of the frame 10. Overlying the stick 18 and the inserts 21 may be a cardboard plate 22 which preferably will be substantially as large as the opening in the frame 10 and will have a more or less even, uniform bearing on the stick 18 and the plywood inserts 21. When the mirror 12 is put in place there may be some compression of the cardboard and the pressure will tend to hold together the flanges 14 and 16 and so hold the insert 15 firmly in place and at the same time place pressure against the reinforcement 17 so as to enhance its effect of reinforcing and holding the insert plate 15.

It will be seen that by this arrangement it is possible to make a sturdy, rigid hand mirror of expensive metal since it may be necessary to employ only a very thin sheet or surface layer of the ornamental metal. Since the insert 15 is separate from the frame itself it is possible to manufacture and keep on hand a considerable number of main frame members 10 and keep on hand a variegated supply of ornamented back inserts 15 so as to promptly fill orders for mirrors of differing types. It may also be possible with a supply of frame members 10 on hand to promptly and economically manufacture a sufficient number of plates 10 having the required and desired ornamental form to promptly fill an order. The wastage in such devices of expensive metal may be considerably reduced and the inventory of parts of precious metal may be considerably reduced by making the frame and the ornamental inserts in separate parts as described. All of this may make it possible to continue to carry on business under what might be otherwise adverse economic and financial circumstances.

It will be understood, of course, that the actual form of the mirror and frame and other details of the invention may be varied within wide limits without departing from the invention claimed.

I claim:

1. In a hand mirror or the like, a thin metallic frame, a hollow handle on the frame, inwardly turned flanges at both front and back of the frame, a thin metal insert sheet, an upwardly turned flange about the periphery of the insert sheet engaging the flange at the back of the frame and holding the plate in the frame, a reinforcing sheet of cardboard cemented on the sheet within the flange, a stick extending from within the handle into the frame at a point opposite the handle, a reinforcing element in the handle holding the stick in place, a pair of reinforcing plywood inserts one on each side of the stick and overlying the cardboard sheet and the flange on the metal insert sheet and pressing the flange into engagement with the flange in the frame, a heavy cardboard member overlying the stick and plywood inserts and holding them in place, a mirror in the front of the frame pressing on the last mentioned cardboard member and holding all parts in more or less rigid reinforcing contact.

2. In a hand mirror or the like, a thin metallic frame, a hollow handle on the frame, inwardly turned flanges at both front and back of the frame, a thin metal insert sheet, an upwardly turned flange about the periphery of the insert sheet engaging the flange at the back of the frame and holding the plate in the frame, a stick extending from within the handle into the frame at a point opposite the handle, a reinforcing element in the handle holding the stick in

place, a pair of reinforcing plywood inserts one on each side of the stick and overlying the cardboard sheet and the flange on the metal insert sheet and pressing the flange into engagement with the flange in the frame, a heavy cardboard member overlying the stick and plywood inserts and holding them in place, a mirror in the front of the frame pressing on the last mentioned cardboard member and holding all parts in more or less rigid reinforcing contact.

3. In a hand mirror or the like, a thin metallic frame, inwardly turned flanges at both front and back of the frame, a thin metal insert sheet, an upwardly turned flange about the periphery of the insert sheet engaging the flange at the back of the frame and holding the sheet in the frame, a reinforcing sheet of cardboard on the sheet within the flange, a stick extending across the frame, a pair of reinforcing plywood inserts one on each side of the stick and overlying the cardboard sheet and the flange on the metal insert sheet and pressing the flange into engagement with the flange in the frame, a heavy cardboard member overlying the stick and plywood inserts and holding them in place, a mir-

ror in the front of the frame pressing on the last mentioned cardboard member and holding all parts in more or less rigid reinforcing contact.

5. In a hand mirror or the like, a thin metallic frame, inwardly turned flanges at both front and back of the frame, a thin metal insert sheet, an upwardly and backwardly turned flange about the periphery of the insert sheet engaging the flange at the back of the frame and holding the sheet in the frame, and means holding the flanges together to hold the insert in place.

10 15 20 25

5. In a hand mirror or the like, a thin metallic frame, inwardly turned flanges at the back of the frame, a thin metal insert sheet, a U-shaped flange about the periphery of the insert sheet engaging the flange in the frame and holding the sheet in the frame, a stiff reinforcing sheet cemented to the insert sheet within the flange, a mirror in the front of the frame, and means between the mirror and the insert sheet holding the flanges together to hold the insert in place.
